CLAIM

The ornamental design for a magnetic tape cassette or similar article, substantially as shown and described.

DESCRIPTION

FIG. 1 is a front, top and left side perspective view of a magnetic tape cassette or similar article showing our new design;

FIG. 2 is a bottom plan view;

FIG. 3 is a rear elevational view;

FIG. 4 is a top plan view of a modified form of a magnetic tape cassette showing our new design wherein the transparent and opaque portions of the band across the reels are reversed; and

FIG. 5 is a top plan view of a second modified form of a magnetic tape cassette showing our new design wherein the transparent and opaque areas of the FIGS. 1 and 2 surface are reversed.

FIG.1

FIG.2

FIG.3

FIG.4

FIG.5
